UNITED STATES PATENT OFFICE

1,923,829

AUTOGRAPHIC REGISTER

Louis Jensen, Chicago, Ill., assignor to United Autographic Register Co., Chicago, Ill., a Corporation of Illinois

Application March 30, 1931. Serial No. 526,535

1 Claim. (Cl. 282—12)

This invention relates particularly to autographic registers and more particularly to autographic registers employing zig-zag folded manifold strips which are drawn from a flat supply packet within the casing of the machine.

The primary object is to provide a hand pull-out machine of improved construction and operation having provision for storing record slips within the machine.

10 This application constitutes a modification of the invention set forth in my application Serial No. 526,534, filed of even date herewith.

The invention is illustrated in a preferred embodiment in the accompanying drawings, in 15 which

Fig. 1 is a perspective view of an autographic register embodying the invention; Fig. 2, a transverse vertical sectional view, taken as indicated at line 2 of Fig. 3; Fig. 3, a longitudinal vertical section view taken as indicated at line 3 of Fig. 2 (the cover shown slightly raised); Fig. 4, a broken vertical sectional view showing the relation between the cover and register pins when the cover is in its normal position; Fig. 5, a perspective view of the rear of the platen showing the guard-aprons; and Fig. 6, a longitudinal sectional view showing one of the guard-apron supporting devices, taken as indicated at line 6 of Fig. 5.

30 In the construction illustrated, A designates a casing comprising a cover A', a platen A², a filling compartment A³, a supply compartment A⁴, and a carbon roll holder or canister A⁵; B, a guide and guard-apron supporting device; and 35 C, a latch or lock for fastening the machine in operative position.

The cover A' has an opening to permit writing on forms supported by the platen and is hinged from the canister A⁵ by means of a pivot 10. 40 The front edge 11 of the cover plate is rounded to provide a smooth guide for strips led over the platen and the marginal side portions 12 are struck downwardly to complete the closure.

The platen A² is connected to the sidewalls of 45 the casing by means of a pivot 13. The platen projects beyond the endwall of the casing to provide a shelf 15 against which the operator may press the strips while tearing off the slips. Register pins 16 are fixedly mounted on the front 50 portion of the platen to engage register perforations in strips drawn over the platen and upwardly extending flanges or lips 17 serve as lateral guides for the strips. The shelf portion of the platen is notched as shown at 18 to provide 55 a finger opening for picking up the slips. The

rear of the platen is curved to form a strip-guide 19 and marginal side portions are struck downwardly to fit over the sidewalls of the casing.

The filing compartment A³ is located beneath the platen and comprises a tray-like member 20 which may be removable through the front of the casing but preferably is fixedly attached to the walls of the casing. A slip-admitting slot 21 and a slanting guide-lip 22 are provided to facilitate feeding of the record slips into the compartment.

The supply-compartment A⁴, in the bottom of the casing, is beneath the filing compartment, and is accessible by means of a door 23 which forms the rear wall of the casing and is hinged 70 at 24.

The carbon-roll container or canister A⁵ is formed integrally with the platen and has a cover-member 25 pivoted to the canister at 26. Carbon strips 27 extend transversely over the platen from a carbon supply-roll and are fastened on the opposite side in the ordinary manner.

The guide and guard-apron supporting device B comprises a pair of upwardly extending flanges or lips 28 formed integrally with the platen, and a series of rods or bars 29 are pivotally connected to a flange on one side of the platen and arranged to fasten into a recess in the flange on the opposite side of the platen. Guard-aprons 30, consisting of a double thickness of fabric, are each provided with a pleat to receive the rod 29. The flanges 28 serve as transverse guides for paper webs 31 which are threaded through the device. The paper webs are of the usual type and are provided with longitudinally spaced register perforations and a transverse line of weakening.

After a set of slips have been filled in, the operator grasps the ends of the strips at the notch 18 and after lifting them from engagement with the pins 16 draws them forwardly until the next set of register perforations are engaged by the pins. It will be seen by reference to Fig. 4, that the edge 11 of the cover A' is so positioned with respect to the pins that the register perforations will be engaged readily by the pins when the strips are drawn forwardly over the platen. To separate the slips the operator presses the strips against the shelf 15, with his finger near one of the register pins, and tears the strips along the line of weakening in advance of the pins. The record slip is then thrust into the filing compartment through a slot in the casing.

The foregoing detailed description has been given for clearness of understanding only, and

no unnecessary limitations should be understood therefrom, but the appended claim should be construed as broadly as permissible, in view of the prior art.

5 What I regard as new, and desire to secure by Letters Patent, is:

In an autographic register, a casing equipped with a platen provided at its front end with register-pins and equipped at its rear end with rods

which are pivotally mounted at one end and which detachably engage at the other end catches with which the platen is equipped, carbon-protecting aprons engaging said rods, and a guide at the rear end of the platen over which stationery strips may be drawn onto the platen, the strips being threaded between said rods.

LOUIS JENSEN.
